UNITED STATES PATENT OFFICE.

LEOPOLD KAHN, OF NEW YORK, N. Y.

DESIGN FOR AN ORNAMENTAL METALLIC WRAPPER.

SPECIFICATION forming part of Design No. 23,115, dated March 13, 1894.

Application filed February 1, 1894. Serial No. 498,799. Term of patent 3½ years.

To all whom it may concern:

Be it known that I, LEOPOLD KAHN, of the city, county, and State of New York, have invented a new and original Design for an Ornamental Metallic Wrapper, of which the following is a specification, reference being had to the accompanying drawing, forming part thereof.

The figure is a plan view of the metal ornamented in accordance with my design.

My design relates to ornamental metallic wrappers used for covering various articles.

The leading feature of my design is the central body portion of open structure, having concentric rib-like figures thereon and the radially-extending arms also of open work, these arms projecting from the sides of the body portion of the wrapper.

The ornamented wrapper showing my de-

sign has a body of circular shape, and the 20 body comprises a central circular figure from which radiate arm-like figures connected at their outer ends, a circular rib-like figure at the outer ends of the radiating arms, a series of small ring-like figures on the periphery of 25 the circular rib, an outer rib-like figure encircling the circle of rings, and a series of radiating arms extending from the outer rib-like figure, the arms being of open-work simulating a lace-like structure. 30

I claim—

A design for an ornamental metallic wrapper herein shown and described.

LEOPOLD KAHN.
